UNITED STATES PATENT OFFICE

ALFRED BURKE, OF NEW YORK, N. Y.

LAMP SHADE FRAME

Application filed July 16, 1931. Serial No. 551,093.

This invention relates to lamp shade frames, and particularly to improvements in the frames of lamp-shades of the type known as "bed-lamps" having supporting hooks whereby the shade is attached to the head-board of a bedstead.

With lamp shade frames of this general type a great deal of care must be taken in preparing them for shipment and in handling because of the fact that the supporting hooks project outwardly beyond the body portion of the frame. It has been found that the supporting hooks are often bent out of shape and not infrequently entirely broken off. Frames of this character are awkward to wrap in paper, and cannot be stacked conveniently for shipment. Furthermore they take up considerable space on the dealer's shelves.

My invention has for an object the elimination of the foregoing and other disadvantages of the present type of bed-lamp frame by the provision of a frame having movable supporting hooks which are adapted to be swung from their operative position into a position within the body of the frame, whereby to protect the hooks from damage in shipping or in handling, and to permit of stacking the frames one on the other.

The invention is not intended to be restricted to the particular constructions and arrangement of parts herein shown and described, as the same may be modified in various respects without departing from the spirit and scope of the invention.

On the drawing, in which the same reference characters refer to the same parts throughout, and in which preferred embodiments of the invention are illustrated:—

Figure 1 is a side elevation of a lamp shade embodying my invention;

Fig. 2 is a view in perspective illustrating the frame with the supporting hooks in their open or operative position;

Fig. 3 is a fragmentary rear view of another form of my invention showing the supporting hook in operative position in full lines, the inoperative position being indicated by dotted lines; and,

Fig. 4 is a transverse sectional view taken on the line 4—4 of Fig. 3.

My invention, in the forms or embodiments shown in the drawing and briefly described, comprises a lamp shade frame, of the bed-lamp type, indicated generally as at 10, and the rotatably mounted supporting hooks 12. The frame 10 is preferably constructed of a pair of superposed wire members 13 and 14 which are bent to the desired shape of the completed shade. These members are held in their spaced relation by means of vertical brace wires 15 and a pair of angularly bent corner supports 16. The lamp socket supporting member 18 may be secured to the upper wire member 14 in any desired manner.

I shall now refer to the supporting hooks and the means for attaching them to the lamp shade frame. In the embodiment of the invention illustrated in Figures 1 and 2, the supports 16 are each provided with a journal, shown generally as at 20, for rotatably supporting the transversely extending wire 21. These journals 20 are preferably fashioned by forming the rear angled edge of the corner supports 16 with a pair of substantially parallel cuts or slits 22, which it will be noted, provides that portion of the corner support with three parallel metallic strips. The two outer strips 23 are bent in an outward direction, whereas the center strip 24 is bent inwardly to provide a substantially circular bearing for the adjacent end of the transversely extending rotatable rod 21.

The hook members 12 are soldered or otherwise fixed to the wire 21 so as to oscillate therewith. The vertical portion 25 of each hook 12 is adapted to bear against the inner side of the cross member 26, which cross member forms a part of the upper wire member 14, so as to limit the outer movement of the hook members. It will be appreciated that the space between the front and rear wires of the upper frame member 14 is sufficient to permit of free movement of the hooks therethrough, or from their outer or frame supporting position, shown in full lines in Fig. 1, to their inner and out of the way position, shown in dotted lines in that figure. In packing the frames for shipment

the supporting hooks are swung into their inner position, in which position the hooks are protected by the frame, and the frames themselves may be stacked one on the other so as to 5 provide a compact arrangement. In use, the hooks are swung into their outer position for engaging the headboard of a bedstead.

In the embodiment of my invention illustrated in Figures 3 and 4, I have dispensed 10 with the wire for supporting both hooks, employing instead an independent pivotal support for each hook. In this connection I provide a pair of spaced bearing portions 30 in each corner support 16' through which are 15 mounted to oscillate the straight portions 31 of the hook members 12. For the purpose of preventing vertical displacement of the hook members 12, and at the same time permitting their free oscillating movement, I have 20 formed the straight portion 31 with angular offsets or bends 32 and 33 at the upper and lower ends thereof, and adjacent the upper and lower bearings 30. These offsets 32 and 33 not only provide means for preventing 25 displacement of the hook members but they also provide an effective means for limiting the outward movement of the hook member 12, as will be clearly seen by referring to Figure 4 of the accompanying drawing.

30 It will be seen that in each of the embodiments of my invention the hook members 12 may be swung easily either into their shade supporting position, or turned inwardly to their out of the way position, whereby the 35 frames may be readily handled, stored in the minimum amount of space, and shipped without attendant danger of twisting or breaking the supporting hooks.

40 The covering of the shade may be of any suitable material, and it may either be permanently attached to the frame, or detachably secured thereto as in the manner disclosed in my copending application, Serial No. 466,390, filed July 8, 1930.

45 What I claim is:

1. A lamp shade frame of the bed-lamp type comprising a pair of upright corner members each having a journal bearing near 50 its upper end, a transverse rod mounted in said bearings, and a plurality of hooks fixed to said rod, said hooks being adapted in one position to extend beyond the frame and to be turned to a second position within the confines of the frame.

55 2. A lamp shade frame of the bed-lamp type comprising a pair of upright corner members each having a journal bearing near its upper end, a transverse rod mounted in 60 said bearings, a plurality of hooks fixed to said rod, said hooks being adapted in one position to extend beyond the frame and to be turned to a second position within the confines of the frame, and a cross member secured to the uprights and disposed in the

path of said hooks for limiting the outward movement thereof.

Signed at New York city, in the county of New York and State of New York this 29th day of June A. D. 1931.

ALFRED BURKE.
